TRANSPORTATION EQUIPMENT

George W. Wilmot, Scranton, Pa.

Application May 6, 1933, Serial No. 669,753

1 Claim. (Cl. 105—366)

This invention relates to improvements in transportation equipment and pertains particularly to a structure which may be transferred from one type of carrier to another.

5 In the shipping of freight from one point to another the material has to be handled a good many times as it is transferred from trucks to trains and then back again from the trains to other trucks to be hauled to the receiver. This 10 constant handling of the goods or merchandise frequently results in the damaging of the containers and consequently of the contents and is particularly injurious to perishable commodities.

The primary object of the present invention is 15 to provide an improved mechanism whereby the units in which merchandise is placed by a sender and kept until delivered to the receiver, may be firmly secured in, or to, a transporting structure such as a railway car, motor car, ship or air vessel, so that the units can not be moved and the 20 contents thereof will be kept safe.

Another object of the invention is to provide a novel means for effecting the locking or fastening of the merchandise containing units on the structures by which they are carried in which the units 25 will be firmly secured against any movement in a horizontal plane as well as against vertical or lifting movement from the structure.

The invention will be best understood from a 30 consideration of the following detailed description taken in connection with the accompanying drawing forming part of this specification, with the understanding, however, that the invention is not confined to any strict conformity with the showing of the drawing but may be changed or modified so long as such changes or modifications 35 mark no material departure from the salient features of the invention as expressed in the appended claim.

40 In the drawing:—

Figure 1 is a view in perspective of the body portion of a car truck showing two units mounted thereon and secured by the locking means embodying the present invention;

45 Figure 2 is a view in perspective of one end of a connected unit beam and chassis cross bar by which the units are coupled with the carrier body;

Figure 3 is a view in perspective of the yoke portion of a unit carried beam which couples 50 with a chassis cross bar;

Figure 4 is a sectional view of the yoke taken substantially upon the line 10—10 of Figure 3;

Figure 5 is a view in perspective of one end 55 of a chassis cross bar with which the yoke member of Figure 9 engages.

Referring now more particularly to the drawing wherein like numerals of reference indicate corresponding parts throughout the several views, the numeral 1 indicates generally the chassis of a unit carrier which in the present case is illustrated as a railway flat car. It is, of course, to be understood that this is merely an illustration of a type of carrier or chassis and may represent the body of a truck, the deck or other suitable supporting structure of a ship or a supporting structure in an air vessel.

The chassis 1 has mounted thereon a series of spaced parallel bars each of which is indicated by the numeral 2. Each of these bars 2 has each end turned at right angles to form the upstanding tongue 3, the inner corner of which is beveled off as indicated at 4 to facilitate its ready insertion into the receiving yoke hereinafter described.

The outer face of each tongue 3 is provided with the transverse semi-circular groove or channel 5 for the reception of a locking pin.

The numeral 6 indicates a merchandise carrying unit. This unit is here illustrated as being in the form of an open receptacle having apertured ears 7 by which it may be readily picked up by a crane and transferred from one carrier chassis to another. It is, however, to be understood that the invention is not to be limited to the use of open receptacles of the character here shown as it will be readily apparent, as the description of the invention proceeds, that closed units may be employed, having wall doors, similar to a box car body.

The merchandise units, of which those indicated by the numeral 6 represent a type, have 35 secured transversely of their bottoms, beams 8 which are preferably of the type known as I beams, having a vertical web portion and the top and bottom plates 10.

Each of the beams 8 has each end secured 40 between the spaced parallel extensions 11 of a yoke unit which is indicated as a whole by the numeral 12. These legs or extensions 11 of the yoke unit form an integral part of one side of an elongated rectangular collar having the outer 45 wall 13, the centrally divided inner wall 14, from which the extensions 11 project, and the connecting end walls 15. The extensions 11 of the yoke unit engage the opposite sides of the web portion 9 of a beam and the plates 10 of the beam 50 overlie the top and bottom edges of these extensions as illustrated in Figure 8. The ends of the beams 8 terminate flush with the inner face of the walls 14 of the yoke head or collar to which they are attached.

Oscillatably mounted in a semi-circular recess or channel 16 formed across the inner face of the wall 13 of each yoke collar, is a semi-cylindrical locking key or bar 17, one end of which extends 5 through an end wall 15 as shown in Figure 3 and is turned to form the actuating handle 18 by means of which the locking pin is rotated.

From the foregoing it is believed to be apparent that the beams 8 secured to the under side 10 of a carrier unit will be spaced apart the same distance as the securing bars 2 carried by the chassis so that when the unit is lowered onto the chassis the tongues 3 of the bars 2 will enter the yokes of correspondingly positioned beams upon 15 the unit as illustrated in Figure 2. The grooves 5 of each of the bar tongues will then be positioned adjacent the groove 16 in the yoke with which it is in engagement and by then giving the locking pin 17 a quarter turn the yoke and tongue 20 will be securely fastened together.

Any suitable means may then be employed for retaining the locking pins in this position to prevent unauthorized movement thereof and removal of the unit from the chassis.

25 While in Figure 1 two units have been shown as mounted upon one chassis it will, of course,

be understood that a single unit or more than two units may be employed, if desired.

From the foregoing it will be seen that merchandise may be readily and safely transported directly from the shipper to the receiver in the 5 actual car or truck bodies and that the units or bodies may be securely fastened upon the carrier and will be held against accidental removal by the locking means described.

Having thus described the invention, what is 10 claimed is:—

Means for coupling a receptacle to a support, comprising a bar secured to the support and having a portion of each end up-turned and provided with a groove extending transversely 15 thereof, a beam secured to the receptacle to be located parallel with said bar between said end portions when the receptacle is on the support, a substantially T-shaped head at each end of said beam having the shank thereof longitudinally divided to receive the beam end and having the transverse portion slotted to receive an up-turned end of the bar, and rotatable means in the said slot of the transverse portion of each T-head for engagement in the groove of an inserted bar portion.

GEORGE W. WILMOT.
